TRIM BLOCK

Anthony L. Kearney and Andrew P. Magnani,
Baltimore, Md.

Application November 23, 1956, Serial No. 43,900

Term of patent 14 years

(Cl. D18—2)

FIG. 1.

FIG. 2.

FIG. 5.

FIG. 6.

FIG. 4.

Fig. 1 is a perspective view of the trim block showing our new design;

Fig. 2 is a top plan view of the trim block;

Fig. 3 is a side view of the trim block shown in Fig. 2, the opposite side of which is identical;

Fig. 4 is a bottom view of the trim block;

Fig. 5 is an end view of the trim block; and

Fig. 6 is an end view of the trim block opposite to the end of Fig. 5.

What is claimed is:

The ornamental design for a trim block, as shown and described.
